UNITED STATES PATENT OFFICE.

WILLIAM HOWARD PAINE, OF PROVIDENCE, RHODE ISLAND, ASSIGNOR TO FIRE PREVENTION COMPANY, A CORPORATION OF RHODE ISLAND.

THERMALLY-CONTROLLED VALVE.

1,147,426.

Specification of Letters Patent.

Patented July 20, 1915.

Application filed May 2, 1914. Serial No. 836,007.

To all whom it may concern:

Be it known that I, WILLIAM HOWARD PAINE, citizen of the United States, and resident of the city of Providence, in the county of Providence and State of Rhode Island, have invented certain new and useful Improvements in Thermally-Controlled Valves, of which the following is a specification.

10 This invention relates to a thermal control of fluid supply for carburetor, and has for its object to provide an attachment for a carburetor comprising a thermal element connected to the carburetor and operative 15 mechanism controlled by said element whereby an excessive heat about the carburetor ruptures said element and causes the float controlled valve to close and automatically shut off the supply of inflammable 20 fluid.

With these and other objects in view, the invention consists of certain novel features of construction, as will be more fully described and particularly pointed out in the 25 appended claims.

In the accompanying drawings, the figure illustrates the carburetor partly in section with my improved thermally controlled shut-off mechanism attached thereto.

30 Referring to the drawing, 10 designates the carburetor, the bowl of which, in the accompanying drawing, is shown partially in section, and a float 11, preferably of cork is located within the bowl and supported on the arm 12, which is pivoted at the point 13. To the opposite end of the arm is connected a valve 14 adapted to close the inlet opening 15 through which opening the supply of gasoline passes, being led thereto from 40 a supply tank not shown, through the pipe 16.

A feature of my present invention is the provision of a thermally controlled mechanism attached to and mounted upon the carburetor itself for the purpose of positively closing this supply control valve, said mechanism comprising a body portion 17 having a hollow center 18, the same being provided with an extension threaded into the opening usually closed by a cap not shown in the carburetor casing directly above the fluid shut-off valve 14. In this hollow center portion is mounted a plunger 19 having a stem 20 extending up through 50 a corresponding hole 21 in the upper end

of said body portion and a spring 22 is coiled about said stem, one end of which rests on the plunger, and the other end against the upper wall of the center chambered portion. An inverted U shaped 60 frame 23 is supported on the upper end of the body portion and the frame in turn supports the upper end 25 of the thermal link 24, the lower end of the link being connected by a hook 26 or other means, to the upper end of the stem 20, whereby the plunger is retained in its upper or inoperative position against the tension of spring 22. This link is constructed in two sections joined together by solder 27 which is adapted to melt 70 at some fixed degree of temperature above normal.

It will be noted that the thermally controlled mechanism is connected to the carburetor at a point above the normal level of 75 the fluid, therefore, there is no necessity of employing a packing, diaphragm or other means of keeping the moving parts either gas or liquid-tight, and therefore, the moving parts may be constructed to work freely 80 in their bearings so that there will be no possibility of corrosion affecting their action thereby greatly simplifying the construction over a thermally controlled valve which is connected to the gasoline pipe similar to 85 that illustrated in my co-pending application Ser. No. 813,816.

It is well known in the operation of internal combustion engines that fire often occurs by what is known as the "back firing" 90 of the engine through the carburetor, which back fire often ignites the gasoline and oil about the carburetor setting the whole on fire, and if the flow of gasoline continues uninterrupted the fire is fed, and great damage often results. But my improved apparatus may be attached directly to the carburetor itself, whereby the ordinary heat controlled valve may be operated upon and closed automatically as soon as the fire 100 starts and held in closed position to positively shut off and prevent further flow of gasoline.

I have shown my improved thermally controlled mechanism as attached to a certain 105 style of carburetor but the same may be connected to a carburetor of any ordinary or commercial float controlled type by simply removing the small cap and screw this device into the carburetor in place thereof. 110

The device is extremely simple in construction and practical and effective in its operation, and by its application to the carburetor, itself, instead of to a valve located in the supply pipe, it is located at the point of greatest danger, and therefore is in position to perform the most effective service.

I claim:

1. The combination with a carburetor 10 having a float chamber, a float mounted in said chamber, and an inflowing fluid shut off valve controlled by said float, of an independent thermally controlled valve closing mechanism mounted on the carburetor, 15 the same comprising a thermal element and means whereby the rupture of said element causes said valve to close and automatically shut off the supply of inflammable fluid.
2. The combination with a carburetor 20 having a float chamber a float pivotally mounted in said chamber, and an inflowing fluid shut off valve controlled by said float, of an independent thermal valve closing mechanism mounted on the carburetor and 25 located above the normal fluid level, said

mechanism comprising a thermal element and means whereby the rupture of said element causes said valve to close and automatically shut off the supply of inflammable fluid.

3. The combination with a carburetor 30 having a float chamber, a float pivotally mounted in said chamber, and an inflowing fluid shut off valve controlled by said float, of an independent thermal valve closing mechanism mounted on the carburetor the same comprising a plunger, a thermal element retaining said plunger in a normally inactive position against a spring 35 pressure whereby an excessive heat ruptures said element and permits the plunger to engage and close said valve and shut off the flow of liquid to the carburetor.

In testimony whereof I affix my signature in presence of two witnesses.

WILLIAM HOWARD PAINE.
